UNITED STATES PATENT OFFICE

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK

DESIGN FOR A BODY ELEMENT FOR AN ELECTRIC-LIGHT FIXTURE

Application filed July 11, 1930. Serial No. 36,327. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Body Element for an Electric-Light Fixture, of which the following is a specification, reference being had to the accompanying drawing, forming part thereof.

In said drawing:

Figure 1 is an elevation of a body element for an electric light fixture embodying my

new design. In this fixture one radial arm and a sector of the central hub are shown in full lines, it being understood that the remainder of the figure shown in dot and dash outline is to be similarly ornamented as the part fully illustrated.

Figure 2 is a plan view of the same similarly illustrated.

I claim:

The ornamental design for a body element for an electric light fixture, substantially as shown and described.

CHARLES W. LOGAN.
